Patented July 22, 1919.

UNITED STATES PATENT OFFICE.

CARL PETERS, OF ST. LOUIS, MISSOURI.

BOAT-LAUNCHING APPARATUS.

1,310,962.

Specification of Letters Patent. Patented July 22, 1919.

Application filed August 6, 1918. Serial No. 248,603.

To all whom it may concern:

Be it known that I, CARL PETERS, a citizen of Russia, residing at St. Louis, in the State of Missouri, have invented a certain new and useful Boat-Launching Apparatus, of which the following is a specification.

This invention relates to life boats carried upon the decks of passenger and cargo vessels and means for launching such boats, and has for its prime object the provision of means for preventing damage to or lateral tilting of the boat while being launched and thus insuring the safety of those taking refuge therein.

In the accompanying drawing, Figure 1 is a side elevation, partly in section, of the boat and launching apparatus as the same would appear upon the deck of a vessel and Fig. 2 is a sectional view of a portion of the boat taken along line 2—2 of Fig. 1.

The launching apparatus comprises four supporting uprights 1 (of which two are shown) which are hinged at 2 to blocks 3 affixed to the deck 4, said uprights carrying weighted latches 5 engaging pins 6 projecting from said blocks. Angle plates 7—7^a are affixed to the upper extremity of each of said uprights and extend above and beneath pins 8 projecting from the retaining bars 9 (of which one is shown), said pins having enlarged heads 10 which bear against the outer edges of said plates and the latter being connected by removable bolts 11, these elements serving to prevent accidental rotation of the frame upon the pedestal herein-after described.

The boat 12 is supported above the deck of the vessel by a steel beam 13 having rollers 13^a disposed beneath the center line of the hull intermediate braces 9 and riveted at 14 to a plate 15 which is pivotally connected at 16 to the compressed head of revolvable cylinder 17, the rear portion of beam 13 being permanently secured at 13^b to an extremity of the retaining braces 9 which are curved inwardly opposite the stern of the boat so as to meet said beam. One extremity of beam 13 is formed integral with an arm 13^c provided with a depending internally threaded lug 13^d which is engaged by threaded rod 18 projecting through stuffing box 19 from the interior of the boat and rotated by means of wheel 20, while the oppo-

site extremity of said beam is provided with a pin 21 for engagement with latch 22 pivotally secured at 23 to beam 24 which is hingedly connected at 25 to beam 13 and provided with wide rollers 25^a, pin 21 also serving as a stop to limit the movement of the curved supporting plate 26 when beam 24 is lowered preparatory to launching the boat.

The lower portion of cylinder 17 is provided (internally) with a transverse plate 27 which rests upon the top of pedestal 28, the latter being inclosed by said cylinder and having an annular flange 29 which is engaged by a plurality of latches 30 secured to said cylinder. Pivotally secured at 31 to beam 13 is a lever 32 which extends through a slot in cylinder 17 and is provided with teeth 33, the latter being retained in engagement with pinion 34 mounted upon lug 35 projecting from said cylinder by straps 36 secured to said lug and said lever being normally retained in the position shown by an arm 37 which is apertured at 37^a for the insertion of a pin which projects through like apertures provided in said lever.

The boat is entered through hatches 38 by aid of ladders 39 affixed to braces 9 and beam 13, said hatches being hinged at 40 to the base of funnel 41 and locked by sliding bolts 42 which engage the cover 43. Within said funnel is an air-inlet tube 44 supplied with a close fitting cover 45 lined with rubber or other like material from which depends a square cut rod 46 terminating in a clamp apertured for the reception of the enlarged head of threaded rod 47, rod 46 being retained against rotation by its projection through a square opening in disk 48 supported by braces 49 and rod 47 extending through a threaded boss 50 fixed to the cover 43.

By reference to Fig. 2 it will be noted that funnel 41 communicates with pipes 51 which extend transversely across the cover of the boat and contain valves 52 provided with depending fingers 53. These pipes are for the purpose of draining said funnel so as to prevent such water as may be carried over the edge thereof from entering the interior of the boat while cover 45 is raised, the water flowing downward past valves 52

so long as fingers 53 rest upon the bottom of valve-housing 54, and the admission of water being prevented by the seating of the conical top of said valves within the neck of said housing as illustrated.

When it becomes necessary to launch the boat and the passengers have taken their places therein, bolts 11 are withdrawn from angle plates 7-7^a so as to release the retaining bars 9 from uprights 1 and the latter are lowered upon the deck of the vessel. Latch 22 is then raised, beam 24 is lowered and the boat, together with bars 9, supporting beam 13 and cylinder 17, is then turned upon pedestal 28 until beam 24 depends over the side of the vessel. During these preparations the boat is maintained in horizontal position by straps 36 and arm 37 in engagement with lever 32, and precipitation of the boat into the water is accomplished by disengaging rod 18 from lug 13^a, the withdrawal of the pin carried by arm 37 and rotation of pinion 34 by crank 34^a so as to force upward the rear end of lever 32 and thus tilt beam 13 upon pivot 16 sufficiently to cause the boat to move forward upon the rollers affixed to said beam and beam 24.

Having thus fully described the several elements of my invention and the operation

thereof, what I claim as new and desire to secure by Letters-Patent is:—

1. Boat launching apparatus comprising a frame rotatably mounted upon the deck of a vessel and adapted to support a life boat, means for maintaining said frame in horizontal position, a lever disposed beneath and attached to said frame, and devices for operating said lever against said frame to tilt the same longitudinally upon release of said means preparatory to launching said boat.

2. Boat launching apparatus comprising a frame rotatably mounted upon the deck of a vessel and adapted to support a life boat, means for maintaining said frame in horizontal position, a lever disposed beneath and attached to said frame, devices for operating said lever against said frame to tilt the same longitudinally upon release of said means preparatory to launching said boat, and a member hingedly connected to said frame affording a support for said boat while the latter is being launched.

CARL PETERS.
